CLAIM

The ornamental design for a transparent wheel having an inner core, as shown and described.

DESCRIPTION

FIG. 1 is a perspective view of a first embodiment of my new design of a transparent wheel having an inner core that illuminates violet/purple using the USPTO convention of vertical dashed lines for violet/purple;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;

FIG. 7 is a back view of the design of FIG. 1;

FIG. 8 is a perspective view of a second embodiment of FIG. 1, in which the inner core illuminates blue using the USPTO convention of horizontal solid lines for blue;

FIG. 9 is a perspective view of a third embodiment of the design of FIG. 1, in which the inner core illuminates green using the USPTO convention of right diagonal solid lines for green;

FIG. 10 is a perspective view of a fourth embodiment of the design of FIG. 1, in which the inner core illuminates yellow/gold using the USPTO convention of horizontal hashed lines for yellow/gold;

FIG. 11 is a perspective view of a fifth embodiment of the design of FIG. 1, in which the inner core illuminates orange using the USPTO convention of diagonal hashed lines for orange;

FIG. 12 is a perspective view of a sixth embodiment of the design of FIG. 1, in which the inner core illuminates red/pink using the USPTO convention of vertical solid lines for red/pink; and,

FIG. 13 is a perspective view of a seventh embodiment of the design of FIG. 1, in which the inner core illuminates white light.

Unless otherwise noted, the broken lines in the above described FIGS. 1-13 are for illustrative purposes only and form no part of the claimed design.
